(57) **CLAIM**

I claim the ornamental design for an air deodorizing apparatus, as shown.

DESCRIPTION

FIG. 1 is a front perspective view of an air deodorizing apparatus comprising the present invention in an open position.

FIG. 2 is a front elevational view of the air deodorizing apparatus shown in FIG. 1.

FIG. 3 is a rear elevational view of the air deodorizing apparatus shown in FIG. 1 and FIG. 2.

FIG. 4 is a side elevational view of the air deodorizing apparatus shown in FIG. 1, FIG. 2, and FIG. 3.

FIG. 5 is another side elevational view of the air deodorizing apparatus shown in FIG. 1, FIG. 2, FIG. 3, and FIG. 4.

FIG. 6 is a top plan view of the air deodorizing apparatus shown in FIG. 1, FIG. 2, FIG. 3, FIG. 4, and FIG. 5.

FIG. 7 is a bottom plan view of the air deodorizing apparatus shown in FIG. 1, FIG. 2, FIG. 3, FIG. 4, FIG. 5, and FIG. 6.

FIG. 8 is a rear perspective view of the air deodorizing apparatus shown in FIG. 1, FIG. 2, FIG. 3, FIG. 4, FIG. 5, FIG. 6, and FIG. 7 in a closed position; and,

FIG. 9 is a top elevational view of the air deodorizing apparatus shown in FIG. 1, FIG. 2, FIG. 3, FIG. 4, FIG. 5, FIG. 6, FIG. 7, and FIG. 8 in a closed position.
